[57] CLAIM

The ornamental design for a miniature chandelier, substantially as shown and described.

DESCRIPTION

FIG. 1 is a side elevational view of a miniature chandelier showing my new design, the opposite side being identical to the side shown;

FIG. 2 is a view from the top of the miniature chandelier shown in FIG. 1; and

FIG. 3 is a view from the bottom of the miniature chandelier shown in FIG. 1.

Fig. 1
